UNITED STATES PATENT OFFICE.

FRANK M. TITUS, OF BRADFORD, PENNSYLVANIA, ASSIGNEE TO BLAISDELL MACHINERY COMPANY, OF BRADFORD, PENNSYLVANIA, A CORPORATION.

COMBINATION GAS-ENGINE-DRIVEN AIR-COMPRESSOR.

1,277,779.

Specification of Letters Patent.

Patented Sept. 3, 1918.

Application filed April 4, 1916. Serial No. 88,939.

To all whom it may concern:

Be it known that I, FRANK M. TITUS, a citizen of the United States, residing at Bradford, in the county of McKean and 5 State of Pennsylvania, have invented certain new and useful Improvements in Combination Gas-Engine-Driven Air-Compressors, of which the following is a specification, reference being had therein to the accompanying drawing.

10 My invention relates to improvements in combination gas engine driven air compressors.

The object of my invention is to provide 15 an engine of this character in which one cylinder is used for the gas engine, and also for compressing the air and using a single piston for both the gas engine and the air compressor.

20 Another object of my invention is to provide a compressor of this character in which means is provided for keeping the cylinder and pistons cool, and providing a simple and more effective compressor having certain details of structure and combination of parts hereinafter more fully set forth.

In the accompanying drawings:

Figure 1 is a longitudinal sectional view of my improved air compressor.

25 Fig. 2 is a sectional view of a modified form of piston.

Referring now to the drawings, 1 represents a cylinder as shown, and is of an elongated form and surrounded by the water jacket 2, whereby the same is kept cool, all of which is well understood in the art of gas engines and needs no further description. The end 3 of the cylinder is closed by a cylinder head 4 having the usual water jacket 5 communicating with the water jacket 2, and is provided with the usual spark plug 6, and the gas intake 7, all of which can be arranged in any desired manner as the specific form of the spark plug, 30 and also the location of the gas intake forms no part of this invention. The opposite end of the cylinder is closed by a cylinder head 8, which like the cylinder head 4, has a water jacket 9 whereby the cylinder is kept cool.

45 50 The cylinder head has a passage 10 leading upwardly through the opening 11, and said opening communicates with a passage 16, which is in communication with a pipe 17 which leads to the tank into which the com-

55 pressed air is to be stored or to any other place desired. Within the passage 16 is a cage 12, which is of a cylindrical form and has its lower end surrounding the opening 11, and has its upper end provided with a screw threaded portion 13, screwed into the 60 head 8. The said cage is provided with a series of openings communicating with the passage 16, whereby the air can pass from the cage. Within the cage is a cylindrical valve 14, resting upon the seat 15, carried 65 by the cage 12. Within the cylindrical valve is a coiled spring 12' which has its upper end bearing against a plug 13', screwed upon the threaded portion 13 of the cage. The cylindrical head 8 is provided with another 70 set of valves 18 which communicates with the cylinder through the passage 19, and communicates with the space 20 which is in communication with the outside atmosphere, whereby the end of the cylinder is supplied 75 with air, later to be described. The valves 18 are of a rotary form and so arranged that they are closed when the piston is moving toward the head 8, by which they are carried so that the air cannot pass out the 80 end of the cylinder but must pass upwardly through the openings 12, controlled by the valve 11.

The cylinder head 8 is provided with a stuffing box 21 through which the piston rod 85 22 passes. This piston rod extends outwardly and is connected through a cross-head and connecting rod to a crank carried by a shaft and on which is arranged the usual fly wheel for balancing the engine. 90 The piston rod 22 within the cylinder 1 is provided with the two pistons 23 and 24 arranged some distance apart and held on the piston rod in said spaced relation. These pistons may be of any desired structure and 95 provided with the usual piston rings 25, all of which is well understood and needs no description. Communicating with a cylinder between the pistons 23 and 24 are the exhaust ports 26, which are so spaced that 100 they are uncovered by the piston 24 when the same has reached its limit of movement at the right end of the cylinder. Communicating with the space between the cylinders to the right of the exhaust ports 26, is 105 an air inlet port or ports 27 which at no time communicates with the space in the cylinder to the left of the piston 24. The

exhaust ports 26 are uncovered just as the piston reaches its limit of outward stroke, and remain uncovered while the crank to which the piston rod is connected is on dead center and allows for the proper exhausting of the burnt gases in the cylinder.

Instead of making the pistons 23 and 24 separate and connecting them to the piston rod 22, as shown in the drawings, the same 10 can be made in one piece and formed of the two pistons 28 and 29 rigidly connected by the sleeve 30 and through which the reduced portion 31 of the piston rod 22 passes as fully shown in Fig. 2 of the drawings.

15 The operation of my device is as follows:

The sparking mechanism is so timed that when the piston 24 reaches its limit of movement to the left in the cylinder, an explosion takes place and forces the piston to the right 20 working against the piston 24. The piston 23 during this movement is compressing the air within the space to the right thereof, and compressed air is forced outwardly through the opening 11 by the valves 12 and out 25 through the passage 16, as heretofore described. As the piston 23 travels to the right, it uncovers the air opening 27 and allows air to pass within the space between the two pistons 23 and 24. The exhaust 30 ports 26 having previously been opened and exhaust gases, after the explosion, passing out of ports 26, causes a partial vacuum in the space between the pistons 23 and 24, and thus when the air passage 27 is opened, a 35 large amount of fresh air is drawn into the space between the pistons 23 and 24 and the pistons kept comparatively cool by said cool air.

The vacuum is caused in the following 40 manner. The piston 24 moves to the right under the force of the explosion and after it has opened the ports 26 by passing the same, the exhaust gases pass out therethrough into the exhaust pipe 32. After the gases have 45 left the cylinder, but are still passing through the exhaust pipe 32, the port 27 is uncovered by reverse movement of the piston 24 to the right and thus both ports 26 and 27 are open at the same time for a short 50 period. The exhaust gases passing through the exhaust pipe 32 create a suction all through the pipe which suction is felt in the space between the pistons 23 and 24, the same being in communication therewith 55 through the ports 26. The suction or vacuum in the space between the pistons 23 and 24 draws a great volume of cool air therein through the port 27, which communicates with the atmosphere. When the pistons 60 have reached their movement to the right, they again travel backwardly to the left, and the passage and the explosive charge is compressed within the cylinder between the cylinder head 4 and the piston 24. The charge 65 is exploded and the piston travels again to

the right, and the same operation takes place. By this construction and arrangement of parts, it will be seen that through the opening of the exhaust openings in advance of the air inlet openings 27 a vacuum is caused between the pistons 23 and 24, and when the piston 23 has passed the air inlet port openings 27, the said vacuum draws in a great amount of fresh cool air, and both aid in cooling the pistons and cylinders. 70

Having thus described my invention what I claim and desire to secure by Letters Patent is:

1. An air compressor of the character described, comprising a cylinder, a piston reciprocatably mounted therein and having a circumferential chamber in its outer periphery, an exhaust port and an air inlet port, the said ports arranged whereby the movement of the piston throws them into communication intermittently with the chamber of said piston. 80

2. An air compressor of the character described, comprising a cylinder, a piston having a circumferential chamber in its outer periphery reciprocatably mounted within the cylinder, means for exploding a charge of gas on one side of the piston, means for compressing air on the opposite side of the piston, exhaust ports adapted to communicate intermittently with the chamber in the piston, and an air port adapted to communicate with the said space whereby the exhaust causes a vacuum therein to draw fresh air into the chamber in the piston for cooling 100 the same. 95

3. An air compressor, comprising a cylinder, a piston having a circumferential chamber in its outer periphery reciprocatably mounted in the cylinder, means for exploding a charge of gas on one side of the piston, means for compressing air on the other side of the piston, exhaust ports for the explosive end of the cylinder and adapted to communicate intermittently with the chamber in the piston, and an air intake communicating with the chamber in the piston, whereby the exhaust causes a vacuum within the chamber in the piston, and whereby when the said air intake is 115 uncovered by the piston cool air is drawn inwardly by the vacuum into the chamber in the piston for cooling the same. 110

4. An air compressor comprising a cylinder having both ends closed, a piston rod 120 extending through one end of the cylinder, a piston carried by the piston rod and formed of two spaced members, means for exploding the charge of gas on one side of the piston, means for compressing air on the opposite side of the piston, exhaust ports adapted to communicate with the space between the two members of the piston, and an air port adapted to communicate intermittently with the said space whereby the ex- 130

haust causes a vacuum therein to draw fresh air between the members of the piston for cooling the same.

5. An air compressor comprising an elongated cylinder having both ends closed, a piston rod extending through one end of the cylinder, a piston carried by the piston rod and formed of two spaced members engaging the inner periphery of the cylinder, 10 means for exploding a charge of gas on one side of the piston, means for compressing air on the opposite side of the piston, exhaust ports for the explosive end of the cylinder and adapted to communicate intermittently 15 with the space between the two members of the piston, and an air intake communicating with the space between the two members of the piston, whereby the exhaust causes a vacuum within the space between the two 20 members of the piston, whereby when the air intake is uncovered by one member of the piston, cool air is drawn inwardly by the

vacuum for cooling the two members of the piston.

6. An air compressor of the character described, comprising a cylinder, a piston having a circumferential chamber in its outer periphery and reciprocating in the cylinder, means for exploding a charge of gas on one side of the piston, means for compressing air on the opposite side of the piston, exhaust ports adapted at one time to communicate with the chamber in the piston, and an air port communicating with the chamber in the piston at the same time the exhaust port is communicating therewith whereby the exhaust causes a vacuum in the chamber to draw fresh air into the same.

In testimony whereof I hereunto affix my signature in the presence of two witnesses. 40
